* cited by examiner

Primary Examiner — Robin V Webster(74) *Attorney, Agent, or Firm* — Westerman, Hattori, Daniels & Adrian, LLP(57) **CLAIM**

The ornamental design for a spray nozzle, as shown and described.

DESCRIPTION

FIG. 1 is a perspective front view of a spray nozzle;

FIG. 2 is a perspective rear view thereof;

FIG. 3 is a right side view thereof;

FIG. 4 is a left side view thereof;

FIG. 5 is a rear view thereof;

FIG. 6 is a front view thereof;

FIG. 7 is a top view thereof; and,

FIG. 8 is a bottom view thereof.

The broken lines illustrate environmental structure only and form no part of the claimed design.
